UNITED STATES PATENT OFFICE.

ROBERT CUMMING ANNAND, OF SOUTH SHIELDS, ENGLAND.

APPARATUS FOR CASTING STEREO TYPE-PLATES.

No. 860,844.

Specification of Letters Patent.

Patented July 23, 1907.

Application filed July 17, 1906. Serial No. 326,639.

To all whom it may concern:

Be it known that I, ROBERT CUMMING ANNAND, of Cornwallis street, South Shields, Durham, England, printers' engineer, have invented certain new and 5 useful Improvements in Apparatus for Casting Stereotype-Plates, of which the following is a specification.

My invention has reference to the automatic supply of molten metal to stereotype casting boxes and its 10 object is to provide an improved apparatus for the purpose, whereby the molten metal can be supplied conveniently and expeditiously to a number of casting boxes disposed around the melting pot.

According to this invention I employ a horizontal 15 swinging arm or arms mounted together with a pump on a vertical pivot in the melting pot, the said arm being adapted to be swung round with the pump to bring the arm over the casting box or boxes. The arm, or arms may be set at an inclination from the horizontal to assist the flow of the metal.

20 The casting boxes are arranged around the melting furnace preferably at a distance from it, so that the heat from the furnace does not inconvenience the attendants.

25 The accompanying drawings represent an example of apparatus constructed in accordance with the invention.

Figures 1 and 2 are respectively a vertical section and a plan of the apparatus; Fig. 3 being a front elevation of the outlet of the radial arm thereof, with the 30 cover plate *k* removed.

a is the melting pot of any usual or suitable kind and heated by a furnace *b*.

c is a radial arm bolted to a pump *d* pivotally mounted with the arm *c* so as to turn therewith in the center 35 of the melting pot in a conical bearing *e* and an upper bearing *e'* in the arm *f* above the melting pot.

g g are valves in the bottom of the pump which allow the metal to enter the cylinder but close when the piston is forced down by the counterweighted hand 40 lever *h* connected to the piston rod *h'* which passes down through an upward extension of the pump cylinder. As shown the lever *h* may work between guides *i* provided with a series of holes through which

a pin may be passed to limit the stroke of the piston and so adjust the amount of metal delivered by one 45 stroke of the pump to the desired quantity in a manner previously known in stereotype casting apparatus. The pivoting arm *c* is formed with a channel *c'* communicating with the pump chamber by a conduit *j* and covered by a plate *k* bolted to the arm *c* and which can 50 be removed for purposes of inspection or repair. The arm is preferably lined with asbestos cement or other non-conducting material *l*, to prevent the metal losing its heat on the way to the casting boxes. The outlet from the arm is directed downwards and widened in 55 the manner shown.

In use, the casing boxes are arranged around the melting pot. The arm *c* is then swung round over the first casting box and the pump is operated to deliver the required amount of metal through the arm *c* into this 60 box. The arm and pump are then turned to bring the arm over the next casting box, and so on. The metal can thus be run into the casting boxes successively in a very practical and convenient manner and without 65 discomfort to the attendant. As the pump turns with the arm or spout, the operating handle always follows it into the required position to be operated by the attendant.

The swinging arm is preferably slightly inclined from the horizontal as shown to assist the flow of the 70 metal.

It will be evident that more than one swinging arm may be employed if desired.

What I claim and desire to secure by Letters Patent 75 is:—

In apparatus for casting stereotype plates, a melting pot, an arm pivotally mounted in the same and adapted to be swung round approximately horizontally to bring it successively over a plurality of casting boxes disposed about the melting pot, and a pump mounted in the melting pot and rotatable with such arm adapted to deliver metal from the pot through the arm to the casting boxes.

In witness whereof, I have hereunto signed my name in the presence of two subscribing witnesses.

ROBERT CUMMING ANNAND.
